COLLAR

Harvey D. Roberson, Leominster, Mass., assignor
to Wachusett Shirt Company, Leominster,
Mass., a corporation of Massachusetts

Application October 21, 1935, Serial No. 45,897

12 Claims. (Cl. 2-143)

This invention relates to wearing apparel and particularly to collars so constructed and arranged to present permanently a stiffened and starched appearance without the application of starch at each laundering operation.

While the invention is applicable to detached collars and other parts of wearing apparel the invention is particularly applicable to soft collars that are permanently attached to the shirt.

One of the objects of the present invention is the provision of an article of apparel and particularly a collar having improved means for stiffening it that is immune to the usual laundering processes and agents and after laundering can be brought into a smooth appearance by the heat and pressure of ironing and will be stiff without the use of starch and other transient stiffening means.

The garment or collar embodying the invention includes a lining fabric or stiffener carrying a cellulosic derivative or other thermoplastic material which contributes to the stiffness of the article and which under the heat and pressure of ironing softens sufficiently to admit of its being bonded to a fabric ply with which it is in pressure contact. A collar has been proposed heretofore having an inner ply impregnated with a fusible stiffening material. A common disadvantage of such a collar is that the stiffening material is liable to be forced through the face ply under the heat and pressing operation and appear on the outer surface of the collar, and particularly at the inturned edge portion thereof, and harm the appearance of the surface so that the collar, and the shirt to which the collar may be attached, is unfit for sale as first class merchandise.

It is an object of the present invention to provide a garment and particularly a collar construction including a stiffener ply having a thermoplastic stiffening material, the collar and the stiffening material being so arranged and disposed that there is no part of the collar that has any excess of stiffening material at the time it is soft under heat and pressure that can pass through an outer ply of fabric and be visible at the surface thereof.

A further object of the invention is the provision of a collar having a stiffener ply interposed between face plies, the stiffener ply having a thin coating only on one face only thereof, and the coated face throughout being confronted with a non-coated fabric so that there is only sufficient coating material to bond the plies together without penetrating the face ply and

also so that there is no superimposition of coatings that can result in such excess coating material that it can pass through a face ply.

A further object is the provision of a collar that can be laundered at home and will have the appearance of a machine finished product.

One of the difficulties experienced in the home laundering of collars is in obtaining a neat wrinkle-free fold in the top or outer part adjacent its junction with the neckband. Hence an important object of the invention is a collar construction, and particularly the arrangement of the plural stiffener plies, wherein the line of fold is demarcated so that the collar folds naturally along the intended line.

For defining the fold line it is an object of the invention to provide the collar top with two stiffener plies, one being extended through the line of fold and secured with the face plies to the neckband and the other stiffener ply being terminated at the fold region so that the collar has reduced stiffness between the upper edge of the second stiffener ply and the neckband and hence folds naturally in this region. Each of the stiffener plies preferably has a thin coating only of thermoplastic material on one face only thereof, the coated faces each confronting a separate face ply and the uncoated faces confronting each other.

It is a further object of the invention to provide a collar wherein the neckband has a stiffener lining provided with a coating of thermoplastic stiffener material that is bonded to a face ply, the stiffener ply, however, stopping short of the folded or inturned edge of the neckband or being of single thickness at said edge so that the neckband where it is attached to the top of the collar and also preferably where it is attached to the body of the shirt is thin.

A further object is generally to improve the construction of wearing apparel and particularly collars.

Fig. 1 is a plan view of an attached collar embodying the present invention.

Fig. 2 is an enlarged sectional view through the folded collar of Fig. 1 and illustrating the invention.

Fig. 3 is a view similar to Fig. 2 but illustrating a modified neckband construction.

Fig. 4 is a view similar to Fig. 2 but illustrating a detached collar construction.

Fig. 5 is an enlarged section taken along line 5-5 of Fig. 2.

Fig. 6 is an enlarged section taken along line 6-6 of Fig. 2.

Fig. 7 is an enlarged section taken along line 7—7 of Fig. 3.

Fig. 8 is a sectional view of the top illustrating the manner of attaching the plies together prior 5 to the turning of the top.

Fig. 9 is a plan view of a neckband face ply and its attached stiffener ply.

Fig. 10 is a sectional view illustrating the manner of securing the neckband plies to the collar 10 top.

Fig. 11 is a sectional view illustrating the manner of securing the shirt body to the neckband.

The invention in Figs. 1, 2 and 3, is illustrated as applied to a soft collar of the attached type, 15 the collar having the neckband portion 10 attached to the shirt body 12 and having a top or downturned outer portion 14. The top 14 comprises front and back fabric face plies 16 and 18, respectively, which can be of any suitable 20 material. The top also comprises a front stiffener ply 20 and a back stiffener ply 22 interposed between and confronting respectively the face plies 16 and 18. The stiffener plies 20 and 22 are preferably composed of a relatively light 25 weight material such as organdie. The outer stiffener lining or ply 20 has on its front face; only, a thin coating 24 of softenable thermoplastic stiffening material. The back stiffener lining or ply 22 has on its rear face only, a similar coating 26. The coatings 24 and 26 impart suitable stiffness to the top and serve to attach the stiffener plies to the adjacent face plies. The stiffener ply, however, is not saturated with the coating material, the coating merely lying upon 30 the surface without impregnating the lining. The amount of coating material is sufficiently little and the character thereof when subjected to heat and pressure also is such that the material does not pass sensibly into or through the face ply 35 with which it is in contact but becomes bonded only to the inner face material of the face ply.

The material forming the coatings 24 and 26 can be of any suitable material that is not deleteriously affected by the usual laundering processes and agents and retains its stiffness and is 40 capable of softening sufficiently under the heat and pressure of the home ironing operation to become smooth and give the collar a fresh stiff appearance. The fusible material can be a cellulosic derivative containing a suitable plasticizer which renders the material capable of becoming 45 soft under the heat and pressure of the ironing operation and regaining its stiffness when cool. A material well adapted for the purpose is cellulose acetate with which is incorporated a suitable 50 plasticizer or agent which enables the coating to become soft under suitable heat and pressure. Other cellulosic derivatives can also be employed.

In assembling the top plies, it is good practice 55 to superimpose the face plies with their outer faces in contact and with the stiffener plies against the face plies, with the coated faces of the stiffener plies outermost, as illustrated in Fig. 8. The plies are then connected together by 60 a line of stitching 30 which extends around the outer edge of the top. The top is then turned or reversed into the form illustrated in Fig. 2 and a finish line of stitching 36 run around the outer edge of the top just clear of the inturned 65 edges of the plies to secure them together.

In accordance with this invention one stiffener ply and particularly the outer stiffener ply 20 is substantially coextensive in width with the width of the face plies 16 and 18 and passes 70 through the bend or fold 38 of the collar. The

rear stiffener ply 22, however, is narrower than the other lining and the face plies and does not traverse the fold line but terminates at 40 under or at the beginning of the bend or fold 38 of the top. The position of the edge 40 hence defines the line of fold. Thus the collar can be folded naturally and neatly by the home laundress at the fold line without the aid of a folding machine. The amount of material in the bend or fold is reduced so that the collar is thin and can be folded readily at the fold line, without wrinkling or buckling because of the thinness of the folded edge and the absence of wrinkles or bulges. The collar is particularly comfortable to wear.

The neckband 10 of the collar, in the modification illustrated in Fig. 2, consists of front and rear fabric plies 42 and 44, respectively, which are composed of any suitable fabric. Between the face plies 42 and 44 are interposed two stiffener plies 46 and 48, respectively, the front ply 46 confronting the front face ply 42 and the back ply 48 confronting the back face ply 44. Both stiffener plies are composed preferably of some light weight or thin material, as organdie, and each has a thin coating 50 and 51 of thermoplastic stiffening material on its opposite faces which in the finishing of the collar are caused to adhere to the back face ply and to the front stiffener ply by heat and pressure, thereby combining all plies into one unitary structure.

The stiffener ply 48 has a thin thermoplastic coating 50 on one face only thereof, which face confronts the back face ply 44. The other stiffener ply 46 has a similar coating 51 that confronts the front face ply 42. Both stiffener plies are narrower at all points than the face ply with which they are associated and are superimposed on the face ply so that the entire marginal portion of the face ply extends beyond the margin of the stiffener ply, as illustrated in Fig. 9 thereby providing the face ply with an edge portion that can be inturned over the stiffener ply all around the margin with a minimum of bulk at the inturned edge. Preferably the face and stiffener ply is united in the aforesaid relation by heat sufficiently to remain positioned while the collar is being finished and until the final pressing operation on the completed collar, thereby to avoid the necessity for stitching the plies together. Both stiffener plies 46 and 48 terminate at the folded or inturned edges of the face plies, both at the top and bottom of the neckband, or are of only single thickness thereat, so that the edge portions of the neckband are 55 thin.

The neckband and top preferably are united as illustrated in Fig. 10. The face plies of the neckband are placed against the face plies of the top with the top edges of both in line and with the stiffener linings outermost. The plies are then secured together by a line of stitching 56 which passes through all plies except the neckband stiffener plies 46 and 48 and the short top stiffener ply 22 at or just above the top edges 65 of the plies 46 and 48. The neckband plies are then reversed in position or are folded along the stitch line 56, as illustrated in Fig. 11. The shirt body 12 is then placed upon the neckband face ply 44 and secured thereto by a line of 70 stitches 57 which pass through the face ply only and beyond the bottom edge of the associated stiffener ply 48. The stitched ends of the shirt body and face ply are then inturned about the bottom edge of the stiffener ply 48 and the 75

free edge portion of the other face ply 42 is also inturned over the bottom edge of its associated stiffener ply 46, as illustrated in Fig. 2, and the inturned edges are secured by a finish line of stitching 54 extended through all plies. The collar is then pressed in a hot bed pressing machine where the heat and pressure soften the thermoplastic coatings and cause them to bond thoroughly to the contacting uncoated plies.

10 Since the collar is more flexible at the fold region 38 than elsewhere, by reason of the omission of the stiffener 22 from the fold region, the collar shapes itself naturally into the fold and without the formation of wrinkles or bulges.

15 In the modification illustrated in Fig. 3, one of the stiffener plies of Fig. 2 is omitted from the neckband and but a single neckband stiffener ply 48a is employed. Said ply preferably is of thicker or heavier material than the ply 20 48 of Fig. 2 and has a thin thermoplastic coating 50a on one face only, which coating confronts and in the finished collar is adherent to the back face ply 44a and is free from adhering to the front face ply 42a. The construction otherwise is the same as described in connection with Fig. 2.

Fig. 4 illustrates in cross-section a detached collar. The construction of the top 14b of the collar is the same as described in connection with Figs. 1 and 2. The neckband 10b is composed of front and back face plies 60 and 62 and has between them stiffener plies 64 and 66. The stiffener plies are composed of some light weight material as organdie and the stiffener ply 64 has a coating of thermoplastic fusible material on its outer face which confronts the front face ply 60. The stiffener ply 66 has a coating of fusible material on its back face which confronts the back face ply 62. The stiffener and face plies have the same width so that their top and bottom edges are coextensive and, in this modification, are inturned with the face plies.

45 In assembling the collar a face ply and associated stiffener ply of the neckband are superimposed and have their edges inturned in a hot bed turning machine which causes the inturned edges of the plies to adhere sufficiently to stay in place. The face plies with their combined stiffener plies are then combined as in Fig. 4 and a line of stitching 70 is started at one end of the band and ran around the bottom edge of the band. When the stitching arrives at the other 50 end of the band the top is inserted and the stitching continued to the place of beginning, thereby connecting the top and band. The face and stiffener plies can, however, be adherently united by a preliminary heating and pressing operation 55 as described in connection with Fig. 2.

60 The use of stiffener plies coated on one side only, which side is in contact with the outer face plies of the collar, is of particular advantage herein as the inturning of the top and bottom edges of the neckband can be readily done by a folding machine, the blades of which do not come in contact with the thermoplastic coating and hence the coatings as disposed in this construction do not hinder the folding operation by sticking to the blades.

70 I claim:

1. A collar comprising a top having front and back face plies and front and back stiffening plies interposed between said face plies, said stiffener plies each having on one face only a

fusible coating of stiffening material, said stiffening coatings confronting and being adherent each to a separate one of said face plies, the uncoated surfaces of said stiffening plies confronting each other.

2. A collar comprising a neckband and a top, there being a fold in the top adjacent its junction with the neck band, said top having front and rear face plies and interposed front and rear linings which are substantially coextensive 10 in length with the length of said face plies and each of which has a coating of fusible material on one face only and is attached by said coating to a separate face ply, one of said linings being terminated short of the fold and the other of 15 said linings being extended through said fold and attached to said neckband, the top being thereby of reduced thickness and readily foldable at the fold line.

3. A collar comprising a neckband and a top, 20 there being a fold in the top adjacent its junction with the neckband, said top having front and rear face plies and interposed front and rear linings the face plies and linings being substantially coextensive in length, one of said linings 25 being terminated short of the fold and the other of said linings being extended through said fold and attached to said neckband, said linings having fusible stiffening coatings on their ply-confronting faces only which are fused respectively 30 to the confronting face plies, the top being thereby of reduced thickness and readily foldable at the fold line.

4. A collar comprising a neckband and a top, 35 there being a fold in the top adjacent its junction with the neckband, said top having front and rear face plies and interposed front and rear linings the face plies and linings being substantially coextensive in length, one of said linings being terminated short of the fold and the other of 40 said linings being extended through said fold and attached to said neckband, said linings having fusible stiffening coatings thereon which are fused respectively to the confronting face plies, 45 each lining having a coating on one face only thereof.

5. A collar comprising a neckband and a top, 50 said top comprising front and rear face plies which are attached to said neckband, said top also containing stiffener plies between said face plies, said stiffener plies being coextensive with the length of the collar, said top having a fold adjacent its junction with said neckband, one of said stiffener plies being extended through said fold and attached to said neckband and the other 55 stiffener ply being terminated below said fold and thereby providing the fold with reduced stiffness as compared with the stiffness of the top, said stiffener plies having coatings of fusible material on only the faces thereof that confront the front and rear face plies and being fused each to a confronting face ply.

6. A collar comprising a neckband and a top, 60 said top comprising front and rear face plies which are attached to said neckband, said top also containing stiffener plies between and substantially coextensive in length with the length of said face plies, said top having a fold adjacent its junction with said neckband, one of said stiffener plies being extended through said fold 65 and attached to said neckband and the other stiffener ply being terminated below said fold and thereby providing the fold with reduced stiffness as compared with the stiffness of the top, said stiffener plies each having a coating of fusible 70 material on one face only of each.

stiffening material on one face only thereof, and said coatings being adherent each to a separate one of said front and rear face plies.

7. A collar comprising as an integral construction a neckband and a top secured together, said neckband having at least one stiffener ply that is fused to the neckband and said top having plural stiffening plies fused to said top, a stiffener ply of said top being excluded from the junction 10 of said neckband, and a stiffener ply of said neckband being of single thickness at the junction of said top and neckband.

8. A collar having a part provided with front and back face plies and interposed front and back stiffener plies, the stiffener plies each having a coating on one face only thereof of a fusible stiffener material which is adherent to the confronting face of a face ply, the uncoated faces of said stiffener plies confronting each 20 other.

9. A collar comprising a neckband and a top, said neckband comprising front and rear face plies and interposed front and rear stiffener plies, said stiffener plies each having a coating of a 25 stiffener material on one face only thereof, which material is adherent to a face of a confronting face ply, the uncoated faces of said stiffener plies confronting each other, said face and stiffener plies having inturned upper and lower 30 edges, a line of stitching uniting said inturned lower edges, said top having an edge portion disposed between said inturned top edges and a line of stitching connecting said top and said inturned top edges.

35 10. A collar comprising a top and a neckband,

said neckband comprising front and back plies having inturned upper and lower edges, a stiffener ply between said face plies having stiffener material adherently united with a face ply, the stiffener ply being of single thickness at the in-turned edges of said face plies, said top having front and back face plies and interposed stiffener plies that are coextensive with the length of the collar and one of which is connected with said neckband and the other of which is terminated 10 short of the connection with said neckband, said top stiffener plies having stiffener material adherently uniting said stiffener plies only with confronting face plies.

11. A collar comprising a neckband and a top 15 secured together, said neckband having an in-turned edge seam at the junction of said neckband and top, said neckband and top having stiffener plies that are coextensive with the length 20 of the collar, a stiffener ply of said top being excluded from the junction of said top and neckband, and said neckband having a stiffer stiffening ply than said top, which stiffer ply is excluded from said inturned edge seam.

12. A fused collar having a top comprising 25 front and rear face plies and at least one interposed stiffener ply, and a neck-band comprising front and rear face plies and at least one interposed stiffener ply, each stiffener ply having a coating of fusible stiffening material on one face 30 only which bonds it to the confronting face ply and throughout the confronting faces and said top stiffener ply being excluded from the fold line of said top.

HARVEY D. ROBERSON.
